CARD HOLDER

John E. Hotchkiss, Corte Madera, Calif., assignor to Hotchkiss Instruments, Inc.

Filed May 27, 1970, Ser. No. 23,167

Term of patent 14 years

Int. Cl. D16—05

U.S. Cl. D61—1 E

Fig. 2

Fig. 1

Fig. 3

Fig. 4

Fig. 5

FIG. 1 is a front elevational view of a card holder showing my new design;

FIG. 2 is a top plan view thereof;

FIG. 3 is a side view thereof;

FIG. 4 is a bottom plan view thereof; and

FIG. 5 is a cross sectional view of the holder of FIG. 1 taken on a plane indicated by the lines 5—5 in FIG. 1.

I claim:

The ornamental design for a card holder, as shown.
